MUZZLE BRAKE FOR GUNS

Gladeon M. Barnes, United States Army,
Hastings, Mich.

Application August 5, 1933, Serial No. 683,754

2 Claims. (Cl. 89—42)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a muzzle brake for guns and is an improvement on the brake disclosed in copending application Serial No. 593,533 of February 17, 1932.

In the application the brake is arranged to utilize a portion of the gases of discharge and then vent the gases in a forward direction. The improvement consists in providing a container to receive and temporarily hold the expanded gases. More specifically the container is formed by a cylinder spaced annularly from the gun barrel.

To these and other ends, the invention consists in the construction, arrangement and combination of elements described hereinafter and pointed out in the claims forming a part of this specification.

A practical embodiment of the invention is illustrated in the accompanying drawing, wherein:

Fig. 1 is a longitudinal sectional view of the improved muzzle brake taken on the line 1—1 of Fig. 2.

Fig. 2 is a sectional view taken on the line 2—2 of Fig. 1.

Fig. 3 is a sectional view of one of the baffle rings.

The muzzle brake comprises an imperforate casing 5 having at its rear end spaced internal ribs 6 whose front or inner faces 7 are substantially flush with the face of the muzzle of a gun barrel 8 when the casing is secured in place thereon as by the threaded connection 9 and pin 10.

A number of passages 11 between the spaced ribs establish communication between the casing 5 and an imperforate cylinder 12 encircling the forward part of the gun barrel. The cylinder is maintained in spaced relation to the gun barrel by virtue of its threaded attachment 13 to the exterior of the casing and its threaded attachment 14 to a ring 15 having a sliding fit on the gun barrel to allow for the differences in expansion between the cylinder and the gun barrel.

Within the casing 5 there are a series of baffle rings 16 specifically claimed in the copending application. Each ring is centered and spaced generally from the casing by means of laterally projecting lugs 17 integral therewith. The baffle rings are maintained in spaced relation with respect to each other by means of axially projecting lugs 18 preferably associated with and forming part of the lugs 17.

The baffle rings, in general, are triangular in cross-section and formed with a concave base 19. The outer lip 20 of the base is provided with recesses 21 each of which is adapted to receive the forward portion of one of the lugs 17 on an adjoining baffle ring. In this manner the baffle rings are locked against relative movement.

The inner most baffle ring 16a abuts against the face 7 of the casing 5 and against the end of the gun while the outermost ring 16b is threaded on the end of the casing 5 and serves to hold the series of baffle rings in place.

In operation when the gun is fired, the gases of the propellant charge follow the projectile and as they emerge from the muzzle of the gun they expanded and pass laterally between the baffle ring 16. The force extorted by the gases on the concave bases of the baffle rings is sufficient to neutralize a considerable amount of the energy of recoil of the gun.

The gases deflected by the baffle rings are directed through the passages 11 and enter the chamber formed between the cylinder 12 and the gun barrel 8. When the pressure in the bore becomes less than the pressure in the cylinder 12 the gases will flow out of the cylinder 12 through the common inlet and outlet passages 11 and then pass between the baffle rings and escape to atmosphere. As a consequence of the forwardly directed dissipation of the gases they will not interfere with the gun crew or raise a cloud of dust by striking the ground.

I claim.

1. In combination with a gun barrel, a casing secured to the muzzle of the gun barrel, baffles within the casing and spaced to provide common inlets and outlets for the transmission of gases, a cylinder encircling the forward part of the gun barrel and spaced therefrom to provide a chamber, the front end of said cylinder attached to the exterior of the casing, a ring having a sliding fit on the gun barrel and attached to the rear end of the cylinder, and a common inlet and outlet between the casing and the chamber.

2. In combination with a gun barrel, a casing secured to the muzzle of the gun barrel, baffles within the casing and spaced to provide common inlets and outlets for the transmission of gases, a cylinder encircling the forward part of the gun barrel and spaced therefrom to provide a chamber, a ring having a sliding fit on the gun barrel and attached to the rear end of the cylinder, and a common inlet and outlet between the casing and the chamber.

GLADEON M. BARNES. 55
